UNITED STATES PATENT OFFICE.

CORNELIUS AMBRUSTER, OF ROSLYN, PENNSYLVANIA.

LAMINATED CONTACT-BRUSH.

1,078,656.

Specification of Letters Patent.

Patented Nov. 18, 1913.

Application filed March 7, 1912. Serial No. 682,164.

To all whom it may concern:

Be it known that I, CORNELIUS AMBRUSTER, a citizen of the United States, and resident of Roslyn, in the county of Montgomery and State of Pennsylvania, have invented certain new and useful Improvements in Laminated Contact-Brushes, of which the following is a specification.

My invention relates to electrical apparatus in which a contact member or brush consisting of a series of laminations is employed to make electrical contact with a contact surface.

My invention consists of certain improvements in the arrangement of the laminations and the angle of their contact surface, whereby a more uniform contact pressure is obtained, as well as a better contact between each lamination and the contact surface than has been possible with the arrangements heretofore used.

My invention will be more clearly understood by reference to the following description taken in connection with the accompanying drawings, in which—

Figure 1 is an elevation of a laminated brush embodying features of my invention, showing the parts when relieved of contact pressure; while Fig. 2 is an elevation of the same brush in contact with the contact surface, and subjected to normal contact pressure.

Referring to Fig. 1, L are the laminations of a contact brush, the thickness of these laminations being somewhat exaggerated for the sake of clearer illustration. Between adjacent laminations are shown spacing pieces S, while on either side of the laminations are shown pressure blocks P¹ and P² which serve to hold the laminations together in their fixed relative positions. The entire

combination of laminations, spacers and pressure blocks may be clamped or bolted together by any suitable device not shown in the drawing.

The spacing pieces S all terminate at a uniform distance from the contact edges of the laminations, so that the projecting ends of all the laminations which are free to bend under pressure are of equal length, and, therefore, an equal amount of deflection produced by pressure will give a uniform pressure between the contact edges of the laminations and the contact surface.

The contact edges of the several laminations are finished at an angle with their longitudinal surface more acute than that of the line 1—2 joining the tips of these laminations in Fig. 1, so that when the brush is just brought into contact with the contact surface without the application of pressure only the tips of the laminations will touch.

The result of applying pressure to the brush is shown in Fig. 2. It will be seen that the application of this pressure bends each lamination by a uniform amount bringing the contact edge of each lamination into full contact with the contact surface A.

Having described my invention what I desire to secure by Letters Patent is—

A contact brush consisting of laminations of which portions project and are free for deflection and have their ends beveled with the points and heels normally in two parallel planes respectively.

In testimony whereof I have hereunto signed my name.

CORNELIUS AMBRUSTER.
